UNITED STATES PATENT OFFICE.

BRICE P. SWYERS, OF PITTSBURGH, PENNSYLVANIA, ASSIGNOR, BY DIRECT AND MESNE ASSIGNMENTS, TO MOTORS LOCK COMPANY OF AMERICA, OF PITTSBURGH, PENNSYLVANIA, A CORPORATION OF DELAWARE.

SAFETY DEVICE FOR STARTING MECHANISMS.

1,242,267.

Specification of Letters Patent.

Patented Oct. 9, 1917.

Application filed June 14, 1913. Serial No. 773,793.

To all whom it may concern:

Be it known that I, BRICE P. SWYERS, a citizen of the United States, and a resident of Pittsburgh, South Side, in the county of Allegheny and State of Pennsylvania, have invented a new and useful Improvement in Safety Devices for Starting Mechanisms; and I do hereby declare the following to be a full, clear, and exact description thereof.

10 My invention relates to safety devices and has special reference to safety devices for preventing the starting of mechanisms such as automobiles, by any surreptitious person during the absence of the person in charge 15 of the same.

The object of my invention is to provide a cheap, simple and efficient form of safety device which will take up very little space and which will be so arranged as to disconnect both high and low tension wires 20 connecting the battery, magneto, and spark plug of the engine, so that in order to connect the same for starting the mechanism, the operator must be familiar with the combination 25 employed.

My invention consists, generally stated, in the novel arrangement, construction and combination of parts as hereinafter more specifically set forth and described and particularly pointed out in the claims.

To enable others skilled in the art to which my invention appertains to construct and use my improved safety device, I will describe the same more fully referring to the 35 accompanying drawings in which:—

Figure 1 is a top plan view of the device.

Fig. 2 is a side view of the same with the casing removed.

Fig. 3 is a cross sectional view on the line 40 3—3 Fig. 2 looking downward.

Fig. 4 is a top plan view of the upper fiber plate showing the contact rings in position.

Fig. 5 is a bottom plan view of the upper 45 fiber plate showing the lower contact rings in position.

Fig. 6 is a bottom plan view of the device with the lower fiber plate removed.

Fig. 7 is a top plan view of the lower fiber 50 plate.

Fig. 8 is a bottom plan view of the same.

Fig. 9 is a plan view of the spring employed in the fiber disk.

Like symbols of reference herein indicate

like parts in each of the figures of the drawing. 55

As illustrated in the drawings my improved safety device has a central shaft 1 which passes through the dial or face 2, the upper fiber plate 3, the fiber disk 4, and the lower fiber plate 5. The dial 2 and upper and lower fiber plates 3 and 5 respectively are supported and held in position by upright supports or standards 6 which are located at suitable intervals around the periphery of such parts and secured thereto in any suitable manner such as by small screws. Fitting around the shaft 1 is a bushing 7 which extends through the dial 2 and through the upper fiber plate 3 and on that portion of the same which extends through the dial 2 is a long hand 8 for indicating the position of the contacts as later explained. 70

At a position between the dial 2 and the upper fiber plate 3 is an arm 9 which is formed of some non-conducting material, such as fiber, and such arm is secured to the bushing 7 in any suitable manner such as by a screw 10 passing through the circular attaching portion 11 of said arm. 75

Upon the upper part of the circular attaching portion 11 of the arm 9 is a bevel gear 12 which is secured firmly to said portion, and adapted to mesh with a small bevel gear 13 as later explained. 80

Secured to the lower face of the dial 2 is a support 14 which carries a bearing 15 for the purpose of receiving a shaft 16, on the inner end of which the said bevel gear 13 is securely located, while a thumb screw 17 is secured to said shaft for the purpose of turning said gear. The thumb screw 17 has a long barrel portion 18 which fits over the end of the shaft 16 and engages by a groove 90 19 on the end of said barrel portion with a pin 20 which extends through said shaft in order to turn said shaft with said thumb screw, while a screw 21 extends into said thumb screw and into the end of said shaft 95 to prevent the parts from becoming disengaged. 100

On the upper face of the upper fiber plate 3 is a series of contact rings three in number, the inner ring 22 being broken at a suitable 105 point and a fiber block 23 is placed in the cavity formed by the gap in the ring as later explained. The middle ring 24 is solid hav-

ing no break in the same, while the outer ring 25 is broken and has a contact 26 in the center of the gap thus formed for the purpose hereinafter explained, while a fiber block 27 is placed on each side of said contact 26 so as to form a smooth even surface at the point of the break in said ring and to insulate said contact from said ring. The inner contact ring 22 is adapted to be engaged by a contact member 28 which is secured to the arm 9 by a screw 29 and such contact member is electrically connected with the bevel gear 12 by a small portion 30 extending onto the upper face of said arm and under said gear. The middle contact ring 24 is engaged by a contact member 31 which has two contact portions 32 and 33 respectively and the said portion 32 rests upon said ring at all times, while the portion 33 rests upon the outer contact ring 25 or the contact 26 in the break formed therein. This contact member 31 is secured to the side of the arm 9 by means of screws 34 and is in no way connected to the contact member 28 on said arm, such member 31 being in contact with the gear 12, and thus grounded through the frame of the device. The inner contact ring 22 is provided with a terminal 35 for attaching a wire, while the middle contact ring 24 and the contact 26 are also each provided with a terminal 36 and 37 respectively, for the same purpose.

Between the upper fiber plate 3 and the lower fiber plate 5 and above the fiber disk 4 is an arm 38 which is secured to the shaft 1 in any suitable manner such as by a screw 39 passing through the circular attaching portion 40 of said arm, and such arm is formed of some non-conducting material such as fiber. At the upper end of the shaft 1 which extends slightly through the bushing 7 a snort hand 41 is secured by a screw 42 which enters the end of such shaft to insure the turning of said hand with said shaft.

The lower face of the upper fiber plate is provided with an inner and outer contact ring 43 and 44 respectively and such rings are each provided with terminals 45 and 46 respectively for the purpose of attaching a wire to the same as hereinafter explained. The outer ring 44 is broken at a suitable point and in the gap thus produced a contact 47 is located while on either side of said contact a fiber block 48 is placed in order to present a smooth even surface and to insulate said contact from said ring. Secured to the arm 38 by means of the screws 49 is a contact member 50 which has two contact portions 51 and 52 and the said portion 51 rests upon the inner contact ring 43 at all times while the portion 52 rests upon the outer contact ring 44 or on the contact 47 located in the break of said ring.

The fiber disk 4 has a round hole 53 in the

center of the same for fitting around the shaft 1 and a bevel gear 54 is attached to said disk by means of screws 55, and a ferrule 56 formed integral with said gear fits around said shaft and is securely fixed thereto by means of a screw 57 bearing against said shaft so as to insure the turning of said disk when said shaft is turned.

Connecting between two of the upright supports or standards 6 is a supporting bar 58 which carries a bearing 59 and a shaft 60 fits through said bearing and has a small bevel gear 60' attached securely to its inner end, while the outer end of said shaft is provided with a thumb screw 61 which has a long barrel portion 62 for fitting over said shaft. The barrel portion 62 on the thumb screw 61 is provided with a groove 63 at the end of the same and such groove is adapted to engage with a pin 64 which extends through said shaft so that said shaft will be turned with said screw. The thumb screw 61 is held securely on said shaft by means of a screw 61' entering the end of said shaft, while the small bevel gear 60' on the inner end of said shaft is adapted at all times to mesh with the bevel gear 54 on the fiber disk 4.

The lower face of the fiber disk 4 is provided with an annular slot 65 and with a recess 66 around the hole 53 which fits over the shaft 1, while a third segment 67 of the material included between said slot and recess is cut out to a depth equal to the depth of the said recess but said slot is of greater depth than said recess and cut out segment.

Fitting around the shaft 1 and located within the recess 66 of the fiber disk 4 is a spiral spring 68 which has two outwardly extending arms 69 which lie within the cut out segment 67 and rest against the side faces 70 formed by said cut out segment, and said arms have each a curved portion 71 continuing out from the ends of the same for fitting within the annular slot 65 between the side faces 70 not included in said cut out segment. The curved portions 71 of the spring 68 are each curved on the same radius as the radius of the annular slot 65 and each of said curved portions are provided at a position immediately beyond the outwardly extending arms 69 with a raised portion 72 as hereinafter explained. That part of the annular slot 65 included between the side faces 70 beyond the cut out segment 67 is covered by a metal plate 73 at about the center of its depth and such plate is adapted to make contact with the curved portions 71 of the spring 68 at all times while said plate will always restrain the curved portions 71 of the spring 68 and prevent the same from leaving said slot. The upper face of the lower fiber plate 5 is provided with an annular raised portion or shoulder 74 for extending into the annular

slot 65 and upon said shoulder are three contacts 75, 76 and 77 respectively which are slightly raised above the upper surface of said shoulder for the purpose of engaging the raised portions 72 of the curved portions 71 of the spring 68 at suitable intervals as hereinafter described. These contacts 75, 76 and 77 are each held in position by a screw 78 formed integral with the same and such screws extend through the lower fiber plate 5 and are engaged by small washers 79 and nuts 80 to hold the contacts in position, while such screws, washers and nuts are adapted to rest in counter sunk holes 81 to protect the same, and to present a fairly even surface on the bottom of said plate. Between the countersunk holes 81 below the contacts 75 and 76 a groove 82 extends for the purpose of connecting a wire 83 between the respective washers 79 and nuts 80.

The outer edge of the lower fiber plate 5 has two cut away portions 84 and 85 between the upright supports or standards 6 for admitting the necessary wires for connection to the hereinbefore enumerated terminals.

The entire mechanism hereinbefore described is contained in a suitable casing 86 which has a glass cover 87 fitting over the dial or face 2 so as to permit of easy inspection of the same at any time.

The device while more or less complicated in description is very simple in construction and will be adapted to be used on all classes of mechanisms where an electric current is used for creating the spark for igniting the gases used in the cylinder or cylinders of the engine.

The device can be attached in a few minutes to any mechanism and when attached it will be practically impossible to start the engine without knowing the combination of numbers to which the respective hands must point before the engine can be given the necessary spark for igniting the gases for operating the same. This device will prove of especial value to owners of automobiles who when leaving their cars standing never have any assurance that the same will be found upon their return, so that by the use of this device the inconvenience and annoyance thus occasioned will be eliminated.

Various modifications and changes in the design, construction, method of connection and operation may be resorted to without departing from the spirit of the invention or sacrificing any of its advantages.

What I claim as my invention and desire to secure by Letters Patent is:—

1. In a combination electric switch, an insulating plate, a set of contacts mounted on one side of said plate, a second set of contacts mounted on the other side of said plate,

a dial, a shaft carrying a hand adjacent said dial, a contact mounted on said shaft and co-operating with the set of contacts on one side of said insulating plate, a rotatable member coaxial with said shaft, a hand carried by said member adjacent said dial, and a contact carried by said member and co-operating with the set of contacts on the other side of said plate. 70

2. In a combination electric switch, a dial, 75 an insulating plate, standards for connecting said plate with said dial parallel thereto and in spaced relation therewith, a set of contacts mounted on one side of said plate, a second set of contacts mounted on the 80 other side of said plate, a shaft passing through said dial and said plate and having a hand mounted thereon, a contact carried by said shaft and co-operating with the said contacts on the lower side of said plate, a 85 sleeve rotatably mounted on said shaft and carrying a hand, and a contact carried by said sleeve and co-operating with the set of contacts on the upper side of said plate.

3. In a combination switch, an insulating 90 plate, a set of ring contacts mounted on one side of said plate, a second set of contacts mounted on the other side of said plate, a shaft mounted through the center of said plate, a contact brush mounted on said shaft 95 and co-operating with the set of ring contacts on one side of said plate, a rotatable member co-axial with said shaft, and a brush contact carried by said member and co-operating with the set of ring contacts on 100 the other side of said plate.

4. In a combination switch, a dial, an insulating base plate, a disk, an insulating plate above said disk, a shaft passing through all of said members, uprights for 105 spacing and holding said plates and said dial in position, a set of ring contacts mounted on the upper side of said second named plate, a second set of ring contacts mounted on the lower side of said second named plate, a brush contact carried by said shaft and co-operating with the contacts on the lower side of said plate, a sleeve rotatably mounted on said shaft and carrying a brush contact co-operating with the ring contacts on the upper side of said plate, and means for independently operating each of 115 said brushes.

5. In a combination switch, a dial, an insulating plate, a disk, an insulating plate 120 above said disk, a shaft passing through all of said members, uprights for spacing and holding said plates and said dial in position, a set of ring contacts mounted on the upper side of said second named plate, a second 125 set of ring contacts mounted on the lower side of said second named plate, a brush contact carried by said shaft and co-operating with the contacts on the lower side of said plate, a sleeve rotatably mounted on 130

said shaft and carrying a brush contact co-operating with the ring contacts on the upper side of said plate, a casing inclosing the whole of said switch, and operating members extending through said casing and in geared connection with said brushes for independently operating them.

In testimony whereof, I the said BRICE P. SWYERS, have hereunto set my hand.

BRICE P. SWYERS.
